UNITED STATES PATENT OFFICE.

CHARLES W. ARMBRUST, OF CHICAGO, ILLINOIS, ASSIGNOR, BY MESNE ASSIGNMENTS,
TO THE AMERICAN BRAKE SHOE & FOUNDRY COMPANY, OF WILMINGTON, DELA-
WARE, A CORPORATION OF DELAWARE.

Brake-Shoe Back.

1,210,383.

Specification of Letters Patent. Patented Dec. 26, 1916.

Application filed January 3, 1916. Serial No. 70,017.

To all whom it may concern:

Be it known that I, CHARLES W. ARM-
BRUST, a citizen of the United States, re-
siding at Chicago, in the county of Cook and
5 State of Illinois, have invented a certain
new and useful Improvement in Brake-
Shoe Backs, of which the following is a
full, clear, concise, and exact description,
reference being had to the accompanying
10 drawings, forming a part of this specifica-
tion.

This invention relates to brake shoe backs
and has for its object the production of a
back which will result in an increase in the
15 wearing qualities of the shoe and permit
its use until the shoe has been worn to its
last possible state of usefulness, and which
will also hold the parts of the shoe in their
proper position with relation to each other,
20 should the same at any time become broken
before the shoe has completely served its
entire purpose.

Another object of the invention is to pro-
duce a back from a blank punched or other-
25 wise formed of sheet metal which results in
that a thinner metal may be used which will
permit the same to be bent to the desired
form and produce a keyway for the key
which secures the shoe to the brake head.

30 A further object is to form apertures
through which the metal of the shoe may
pass to form a means whereby the shoe and
back are held together. The blank is fur-
ther designed to produce portions which may
35 be embedded in the shoe proper and which
form a means whereby said shoe and the
back are further held together.

40 A further object is to produce these and
other advantages in a simple, efficient and
inexpensive manner without resulting in a
corresponding reduction of efficiency, and
requiring no special machinery for its pro-
duction.

45 I will explain the invention by referring
to the accompanying drawings, in which—

Figure 1 is a view partially in section of a
brake beam and head showing the relative
position of a shoe having my improved back
applied thereto; Fig. 2 is a front view of a
50 shoe having a construction similar to that
shown in Fig. 1, and showing my improved
back applied thereto; Fig. 3 is a transverse
section on line *a—a* of Fig. 2; Fig. 4 is a
plan view of a blank of which one form of

the back may be formed; Fig. 5 is a detail 55
view of the back separated from the shoe
and bent to form a back from the blank
shown in Fig. 4; Figs. 6, 7 and 8 are plan
views of modified forms of construction;
Fig. 9 is another modified form of construc- 60
tion in which the extreme ends of the back
are provided with means against which the
ends of the brake head may rest; Fig. 10
shows a brake shoe provided with a back
having the construction shown in Fig. 9 65
and showing the ends of the brake head co-
operating therewith; Fig. 11 is a transverse
section of a brake shoe having a back ap-
plied thereto of a construction similar to
that shown in Fig. 7; Fig. 12 is a transverse 70
section of a brake shoe having a back ap-
plied thereto similar to that form shown in
Fig. 8; Fig. 13 is a transverse section of a
brake shoe showing a modified application of
the form of construction shown in Fig. 8; 75
Fig. 14 is a transverse section of a brake
shoe showing a keyway entirely embedded
in the metal of which the shoe is formed;
Figs. 15, 16 and 17 show several ways in
which the back may be positioned and held 80
with relation to the shoe, for instance, Fig.
15 illustrates the back as entirely embedded
in the shoe with the exception of the portion
which forms the keyway, the remaining
views illustrating the same portions of the 85
back partially mounted within the shoe and
wholly outside of the metal which forms the
shoe. Fig. 18 is a modified form of con-
struction, in which the construction of the
side edges of the plate are entirely relied 90
upon to produce the means whereby the back
is secured to the shoe; Fig. 19 is another
modification, showing an arrangement
whereby the thickness of the shoe is slightly
increased to accommodate the means which 95
serve to secure the back and shoe together.

Referring more particularly to Fig. 1, I
show a brake shoe having my improved back
applied thereto, and also illustrating the
shoe as applied to a brake beam and head 100
and showing the ordinary manner of secur-
ing said shoe in position with relation to the
brake head.

Referring more specifically to the parts
shown in Fig. 1, I show a brake beam 18 105
which carries the brake shoe head 19, the
key 20, and a shoe 21 having my improved
back 22 applied, and carried by the head.

As before stated, the back is preferably formed of a blank punched or otherwise formed of thin metal. This blank is generally designated 23 and particularly shown in Fig. 4. As shown, this blank is comprised of the side members 24 and 25 and the transversely arranged portion 26. The portion 26 is designed to be bent outwardly upon lines 27-27, 28-28, and when bent forms a keyway 29 for the key 20 illustrated particularly in Fig. 1. It will be noted that when the keyway is bent as illustrated, the opening provided thereby through which the key 20 is passed is arranged so that its sides and top are parallel with the body of the shoe, thereby resulting in greater strength and stability of this part 29 by virtue of the fact that the same is connected throughout its whole length with the portion which forms the brake shoe back. It will be further noted that the blank 23 is provided with the cut-away portions 30 and 31 provided at each side of the portion 26 of which the keyway 29 is formed.

It will be evident by reference to Fig. 5 that when the blank is bent to form the member 29 that the inner edges of the members 24 and 25 will be brought together to result in the cutaway portions 30 and 31, producing the apertures 32, 32, preferably provided at each side of the member 29. These apertures 32, 32 form a means through which the metal of the brake shoe may pass, and assist in producing a holding means to secure the back and the shoe together.

By referring particularly to Fig. 2 it will be noted that the shoe is provided with the raised portions 33, 34 and 35, which form seats against which the brake head 19 may rest. It will be further noted that lugs 36 and 37 are also utilized which are provided with the cut-away portions 38 and permit the key 20 to be positioned to hold said shoe and head together. These seats and lugs will be found in all shoes constructed in accordance with the usual M. C. B. standard type of shoe. It will be noted that the back is embedded at both ends and in the middle in these seats, the remaining portion of the back being partially embedded in said shoe. It will further be noted that the member 29 protrudes a considerable distance beyond the shoe. This permits the key 20 to be readily passed therethrough to secure the brake shoe in position upon the brake head.

In the form shown in Fig. 7, the side edges of the brake shoe and the edges of the aperture 32 are shown provided with the beveled portions 39. This feature is also illustrated in Fig. 11 from which it will be evident that the members similar to those designated by the numerals 24 and 25 will be substantially wedge shaped in cross section. The smaller portion of the wedge formed by this con-

struction will preferably be faced toward the outer portion of the shoe and be embedded in the body portion of the shoe, thereby greatly decreasing the possibility of separation occurring between the parts to which the back is applied. 70

In the construction shown in Figs. 8 and 12, the side edges of the back only are beveled and the members 24 and 25 are provided with lugs and recesses 40 and 41, the lugs being preferably of a length which when bent downwardly will extend into the metal of the shoe only a distance equal to the thickness of the metal of which the back is formed. In this form of construction said lugs form the holding means whereby the shoe and the back are held together. 75 80

In Fig. 13 I contemplate the use of a construction which is similar to that shown in Fig. 12, differing only in that the back is shown as being embedded in the shoe and having beveled side edges. Lugs similar to those shown in Fig. 12 are also utilized to prevent the shoe from becoming separated from the back. 85

Figs. 9 and 10 illustrate another form of construction which my invention may take. In this form lugs 42 and 43 and the raised portions 44, 45 and 46 are all produced in the metal of which the back itself is formed, 90 which form portions against which the brake head may rest. The purpose of the lugs 42 and 43 is illustrated in Fig. 10. The raised portions 44, 45 and 46 produce seats against which the faces 47 and 48 of the brake head may be placed when the shoe is applied thereto. In this form the back will be provided with the forked ends 49 and 50 and the portion 45 will extend completely across to the side edges of the metal of which the back is formed, and the lug 29 will be formed in this intermediate portion 45. This construction permits the portion of the members 24 and 25 between the portions 44 and 45, and 45 and 46, to be 95 100 105 embedded in said shoe and the metal of the shoe permitted to flow into the recesses formed by the raised portions 44, 45 and 46, and thereby produces coöperating shoulders and recesses which will hold the back 110 and shoe together. 115

The construction shown in Fig. 18 is designed to eliminate the necessity of additional lugs, apertures, etc. This may be accomplished by beveling the side edges of the back as indicated at 51. This will cause the back to resemble a wedge in cross section, which when embedded in the metal of the shoe, will prevent its separation therefrom. 120

In the form illustrated in Fig. 19 the shoe will be provided with an offset portion 55. This offset will correspond in thickness to the length of the lugs 56, which form the means whereby the parts are held against 130

separation. By this arrangement the usual thickness of the shoe itself will be slightly increased, but will result in producing a shoe having the same wearing surface as 5 ordinarily, minus the possibility of scoring the tread of the wheel which might be caused by projections or lugs 56 when the shoe has been worn to this point.

It will be evident from the foregoing that 10 the back may be formed of substantially thin metal and that a means is produced whereby the parts are securely held in place with relation to each other, and also that the construction herein shown produces a means 15 whereby the parts are securely held together even though the shoe should become broken from any cause before it has served its entire purpose, and before it has been reduced to a state of uselessness from wear. 20 Also that a means may be easily formed for holding the brake head and the shoe against any lateral movement with relation to each other, all of which may be accomplished in a comparatively cheap manner without re- 25 sulting in a consequent reduction of efficiency.

Having thus explained my invention, what I claim as new and desire to secure by Letters Patent is:

30 1. A brake shoe back comprising a plate

which is constructed to be bent to form a holding member and to produce apertures therein when bent, said apertures forming a means through which the metal of said shoe may pass to form a means whereby said 35 shoe and back are held together, said apertures and said holding member being formed from a blank which is composed of laterally separated recessed portions and a member which extends across and connects said 40 laterally separated members, which when bent causes the recessed portions to be brought together and form said apertures.

2. A brake shoe back comprising a plate having recessed portions, said plate being 45 constructed to be bent to form an apertured projection to receive a key, said recessed portions forming an aperture when said plate is bent through which the metal of the shoe may pass to secure said shoe and 50 back together, and downwardly extending strengthening ribs at the side edges of said plate.

In witness whereof, I hereunto subscribe my name this 16th day of December, A. D., 55 1915.

CHARLES W. ARMBRUST.
